22 pass over pulleys 27 secured to the casing 1 and carry weights 28 which are the regular lower sash weights; said weights being operatively connected by said cords 24, 26 5 and drums 21, 22 to the lower sash 2, this connection being undisturbed whether the said drums 21, 22 are loose or fast upon the shaft 19. When the screens 13, 17 are connected, respectively, to sashes 3, 2 the drums 10 7, 8 and 21, 22 are made fast to their respective roller shafts 9, 19 by means of the cotter pins 10, 23. The weights 15, 28 then cause the rolls of the roller shafts to wind upon themselves the flexible screens as the window sashes are moved into closed position 15 and said screens will unwind as the sashes are moved into open position. In the winter season the screens may be detached and left in the window casing upon their roller shafts. The cotter-pins 10, 23 are now removed from the drums and passed through openings 29 in the brackets 11, 20 and in shafts 9, 19 thereby locking said shafts stationary and leaving the drums loose upon 20 said shafts. Raising and lowering of the sashes now will raise and lower the weights but the cords of said weights will pass over and rotate the drums independent of their shafts.

30 The upper sash is formed with a socket 30 and the lower sash is formed with an aperture 31 through which the bolt 32 provided with handle 33 is projected and adapted for releasable engagement with said socket 30 to retain said sockets in open position, the shape of the upper rail of the lower sash and of the lower rail of the upper sash being such that, in this locked open position, it is impossible for insects to pass therebetween. A socket 34 may also be formed in the lower rail of the upper sash to receive the bolt 32 whereby the sashes may be locked in closed position.

Without the locking device it will be 45 noted the sashes could not be opened at the same time. The upper sash may be lowered without the use of a window pole by first raising the lower sash into wide open position or until the spring bolt 32 engages 50 the socket 30 and both sashes are then lowered together into half-open position, opening the window at top and bottom.

What is claimed is:—

1. The combination with a longitudinally grooved window jamb of a flexible upper screen secured to the upper sash, a flexible lower screen secured to the lower sash, roller

shafts for said screens, sectional drums carried by said roller shafts, a weight flexibly connected to one section of each of said drums and flexible connection between the other drum section and one of said sashes. 60

2. The combination with a longitudinally grooved window jamb, of a flexible upper screen detachably secured to the upper sash, 65 a flexible lower screen detachably secured to the lower sash, roller shafts for said screens, sectional drums terminally carried by said shafts and adapted to be made fast thereto when said screens are in operative 70 position, flexible connection between said drums and said sashes and means operatively associated with said drums when said screens are in operative position whereby said drums may be given a tension to 75 permit the winding thereupon of said flexible screens.

3. The combination with a longitudinally grooved window jamb, of a flexible upper screen detachably secured to the upper sash, 80 a flexible lower screen detachably secured to the lower sash, a socket formed in the upper and lower rails of the upper sash, a spring bolt carried by the upper rail of the lower sash for releasable locking engagement with either of said sockets, roller shafts 85 for said screens, sectional drums carried by said roller shafts, a weight flexibly connected to one section of each of said drums and flexible connection between the other 90 drum section and one of said sashes.

4. The combination with a longitudinally grooved window jamb, of a flexible upper screen detachably secured to the upper sash, 95 a flexible screen detachably secured to the lower sash, roller shafts for said screens disposed in the window casing, means carried by each sash for releasable mutual engagement whereby the lower sash may be operated to open and close the upper sash, sectional drums carried by said roller shafts, a weight flexibly connected to one section of each of said drums and flexible connection between the other drum section and one 100 of said sashes.

In testimony that I claim the foregoing as my own I have hereto affixed my signature in the presence of two subscribing witnesses.

ELWIN SWANSON.
